UNITED STATES PATENT OFFICE.

ERNEST DAVIS, OF SYRACUSE, NEW YORK, ASSIGNOR TO THE PROSPERITY COMPANY INC., OF SYRACUSE, NEW YORK, A CORPORATION OF NEW YORK.

HEAT-DISTRIBUTING MEANS.

Application filed July 3, 1926. Serial No. 120,362.

This invention relates to ironing elements, having means for heating them as a burner or other heater where the heat is necessarily localized in spots, and has for its object a 5 particularly simple and efficient means for distributing the heat from the heating element evenly through the ironing face of said element.

The invention is particularly adapted for 10 pressing machines having a heated head movable toward and from a buck upon which the work is mounted, but it is also equally applicable to flat irons as gas heated or electrically heated flat irons and the like.

15 The invention consists in the novel features and in the combinations and constructions hereinafter set forth and claimed.

In describing this invention reference is had to the accompanying drawings in which 20 like characters represent corresponding parts in all the views.

Figure 1 is a fragmentary side elevation of a pressing machine provided with my invention.

Figure 2 is an enlarged fragmentary transverse sectional view through the head of the machine, or an enlarged sectional view on line 2—2, Figure 3.

Figure 3 is a plan view, partly broken away of the head,

Figure 4 is a sectional view on line 4—4, Figure 3.

This invention comprises, generally, an ironing element formed with an ironing face, 35 and means for distributing the heat substantially throughout the ironing face.

My invention is here illustrated as embodied in an ironing element having a burner or heater for heating said element, and the 40 element is formed with a chamber overlying the former chamber in which the burners are located, the chambers being separated by a metal partition. Obviously in ironing elements having such burners, the heat is localized or the ironing face will be hot in spots.

The means for distributing the heat throughout the ironing face is here shown as a body of metal wool substantially filling the chamber, which overlies the ironing face, 50 said metal wool being of a metal, as copper, having a greater heat conductivity than the metal of the ironing element.

The ironing element is here shown as the head 1, of a pressing machine which head is 55 movable toward and from the buck 2 suit-

ably mounted upon the frame of the machine, the head 1 being mounted on a yoke or lever 4 pivoted between its ends to a standard 5 rising from the frame 3.

The head is here shown as formed with a 60 chamber 6 over-lying its ironing face 7, and with a second chamber 8 above the chamber 6, the chambers being separated by a horizontal metal partition 9. The chamber 8 is formed with suitable air holes 11 for the 65 escape of the products of combustion and also for the inlet of air to support the combustion at the burners.

The burners as here illustrated are a series 70 of pipes 12, located in the chamber 8 and having jet or burner openings 13, these pipes 12 being connected to a main feed pipe or conduit 14 formed in the buck. The passage 14 is connected to a suitable source of supply through a pipe 15 and coupling 16. The 75 partition 9 is formed with suitable posts or projections 17 on opposite sides thereof and the lower wall of the chamber 6 is likewise formed with upward projections 18, all for facilitating the distribution of the heat. 80

19 is the body of metal wool packed in the chamber 6, this wool as before stated being copper shavings or copper wool. Owing to the metal wool having a greater heat conductivity than the metal of the head, which is usually cast iron the heat from the burners 12 is evenly distributed throughout the ironing face 7.

What I claim is:

1. In an ironing element the combination 90 of a body having an ironing face, heating means within the body and means for distributing the heat throughout the ironing face including a body of metal wool having greater heat conductivity than the metal of the body.

2. In an ironing instrument the combination 100 of a body having an ironing face, a chamber overlying the ironing face and a heating chamber overlying the former chamber by a partition wall, the former chamber having a body of metal wool filling the same and engaging all the walls of said chamber and said partition wall, the body of metal wool 105 having greater heat conductivity than the metal of the body.

3. In an ironing element, the combination 110 of a body having an ironing face, a chamber overlying the ironing face, a heating cham-

ber overlying the former chamber and having a burner therein and a body of metal wool in the former chamber and separated therefrom by a partition wall, the body of metal wool having a greater heat conductivity than the metal of the ironing element.

4. A pressing machine comprising a buck and a head movable toward and from the buck, the head comprising an ironing or 13 pressing element, the head being formed with a chamber overlying its ironing face and a heating chamber overlying the former chamber and separated therefrom by a par-

tition wall, and means for distributing the heat from the heating chamber throughout the former chamber and throughout the ironing face of the head, said means comprising a body of metal wool filling the same having a greater heat conductivity than that of the metal of the head.

In testimony whereof I have hereunto signed my name at Syracuse, in the county of Onondaga and in the State of New York, this 30th day of June, 1926.

ERNEST DAVIS.
